UNITED STATES PATENT OFFICE.

CHARLES F. HUNTOON, OF CHICAGO, ILLINOIS.

BRAKE-BEAM SUPPORT.

1,427,474.

Specification of Letters Patent. Patented Aug. 29, 1922.

Application filed July 11, 1921. Serial No. 483,834.

To all whom it may concern:

Be it known that I, CHARLES F. HUNTOON, a citizen of the United States of America, and a resident of Chicago, county of Cook 5 and State of Illinois, have invented certain new and useful Improvements in Brake-Beam Supports, of which the following is a specification.

This invention relates to brake beams, and 10 particularly to the supporting and guiding means which insure the desired radial motion of the brake heads toward and away from the car wheels during an application or release of the brakes. The objects of the invention are to provide additional supporting guiding means over the usual hangers, which additional supporting and guiding means is attached to the brake beam and extends upwardly over the spring plank 15 in order to avoid the objections to third suspensions or additional supporting means for the brake beams which necessitate projections below the spring plank and are dangerous in case there is an obstruction between 20 the rails such as a bent or broken tie or crossing plank. A further purpose of the invention is to simplify the design of such additional suspending and guiding means for the brake beam, and to utilize the spring 25 plank as a support over which such additional supporting and guiding means is movable.

The objects of the invention are accomplished by the device shown in the accompanying drawings, in which

Figure 1 is a fragmentary plan view of a brake beam provided with the present improvements.

Figure 2 is an end view, taken from the 40 left of Figure 1, and showing part of the spring plank and the compression member in section for the sake of clearness.

The brake beam illustrated is of standard design with respect to its main elements, the 45 strut, the compression and tension members, and the brake-shoe supporting heads. Likewise, no alteration is made in the usual spring plank, but this is utilized to afford an additional support over the usual hangers 50 which are pivotally connected with the brake heads. Guiding straps are clamped to the compression member inwardly of the location of the brake heads, and these guiding straps are bent to project over the spring 55 plank, and preferably pass through apertured fixed guides which are riveted to the

vertical flange of the spring plank adjacent the brake beam. By this construction, when the brake beam moves toward or away from the car wheels, the beam in swinging from 60 its hanger supports, is guided about the additional suspending means so as to have the desired pivotal action around the hangers in order that the brake-shoes move radially of the wheels. If one of the usual hangers 65 becomes broken, the additional supports extending over the spring plank prevents the beam from falling.

Referring to the drawings, the brake beam is shown as including the usual strut 70 1, compression member 2, tension member 3, and brake heads 4. The brake beam is suspended by means of the usual swingable hangers, 5, shown partly broken away in the drawing. These hangers at their lower end 75 are pivotally connected with the brake heads, and, therefore, the brake beam may have a slight pivotal motion on its hanger support, and, therefore, need not move away and toward the wheels in an arc which is 80 not radial to the axes of the wheels. The spring plank of usual design is indicated by the numeral 6. Projecting over the spring plank, preferably near each end of the brake beam, is a pot-hook shaped supporting member 85 7. This additional support is yoked around the compression member 2 at its outer end 8 and is securely clamped to the compression member by the bolt 9. The inner slightly curved portion 10 of each additional support 7, passes through an aperture 11 in a guide 12, riveted to the vertical flange of the spring plank. The curved shape of the support 7 and its engagement 90 with the guide 12, insures the necessary slight pivotal motion of the brake beam on hanger 5 when the brake beam is swung between the full line and dotted line positions shown in Fig. 2.

In the operation of the device, a movement 100 of the brake beam in an application or release of the brakes, results in the brake-shoes maintaining parallelism with the wheel tires, due to the fact that the additional supports are properly guided over the spring 105 plank 6. These additional supports, as designed, do not require any dangerous downwardly projecting parts, or necessitate unsafe wear on any part of the mechanism, and are readily replaceable if injured.

Although but one specific embodiment of this invention has been herein shown and

described, it will be understood that numerous details of the construction shown may be altered or omitted without departing from the spirit of this invention as defined 5 by the following claims.

I claim:

1. In a railway car, a brake beam provided with brake-shoe heads at its ends, hanger supports for the beam, a spring 10 plank, an additional support and guide for the brake beam, said additional support and guide being movable with the brake beam and projecting therefrom to be slidable over the spring plank.
- 15 2. In a railway car, a brake beam provided with brake-shoe heads at its ends, hanger supports for the beam, a spring plank, additional supports and guides for the brake beam located between the center 20 and ends of the brake beam and movable with the brake beam, means on said spring plank for slidably supporting said additional supports and guides, and said additional supports and guides being formed to 25 project over the spring plank for sliding engagement with said means.
3. In a railway car, a brake beam pro-

vided with brake-shoe heads at its ends, hanger supports for the beam, a spring 30 plank, an additional support and guide clamped to the brake beam, said additional support and guide being movable with the brake beam and projecting therefrom to be slidable over the spring plank.

4. In a railway car, a brake beam provided with brake-shoe heads at its ends, 35 hanger supports for the beam, a spring plank, a guide secured to the spring plank, and an additional support and guide for the brake beam rigid with the brake beam and 40 slidably engaging said guide on the spring plank.

5. In a railway car, a brake beam provided with brake shoe heads at its ends, hanger supports for the beam, a spring 45 plank, apertured guides secured to the spring plank, and additional supports and guides for the beam movable with the beam and slidably projecting through said apertured guides on the spring plank. 50

Signed at Chicago this 18th day of June, 1921.

CHARLES F. HUNTOON.
